UNITED STATES PATENT OFFICE.

VICTOR R. BOTTONE, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA.

PUNCHING-MACHINE.

1,344,435.

Specification of Letters Patent. Patented June 22, 1920.

Application filed October 29, 1918. Serial No. 260,169.

To all whom it may concern:

Be it known that I, VICTOR R. BOTTONE, a subject of the King of Great Britain and Ireland and the Isle of Man, residing in 5 Philadelphia, Pennsylvania, have invented Punching-Machines, of which the following is a specification.

One object of my invention is to provide a simple and substantial form of punching 10 machine, especially designed for perforating thin sheets or plates of structurally weak material, such as the hard rubber employed in the manufacture of separators for use in storage batteries;—the invention 15 more particularly contemplating a novel form and arrangement of the punches and coöperating die structures for forming the very narrow elongated perforations desired in such structures.

20 I further desire to provide a novel construction of feed rollers for insuring the proper intermittent delivery of the thin sheets of material to the punches.

Another object of my invention is to provide 25 novel means for mounting the individual members of a gang of punches in a head or supporting block whereby it shall be possible to quickly and conveniently remove and replace any of said punches;— 30 the invention also including novel forms of the die and the stripper plate for co-operating with the punches.

These objects and other advantageous 35 ends I. attain as hereinafter set forth, reference being had to the accompanying drawings, in which—

Figure 1 is a front elevation of a punching machine constructed in accordance with my invention;

40 Fig. 2 is a side elevation of a portion of the machine shown in Fig. 1;

Fig. 3 is a rear elevation, partly in section, on the line 3—3, Fig. 2, further illustrating the invention;

45 Fig. 4 is an enlarged transverse vertical section of the punch and die supporting structures with their associated parts;

Figs. 5, 6 and 7 are fragmentary perspective views of the punch-carrying plate, the 50 stripper and the die, with their associated parts;

Fig. 8 is a fragmentary perspective view, partly in section, illustrating the detail construction of one end of part of the die;

Fig. 9 is a transverse vertical section 55 showing a modified construction for the ends of the spacer plate; and

Fig. 10 is a fragmentary perspective of one of the completed separator plates made by my machine.

In manufacturing the thin, hard rubber separators of the type shown in Fig. 10, which are required in certain well known forms of storage batteries, the blank rubber sheets, having a thickness in the neighborhood of .015 of an inch, are required to be provided with series of relatively narrow elongated slots 1 whose width is preferably somewhat less than the thickness of the sheets in which they are formed. These 70 slots are relatively close together and for properly forming them in the blank rubber sheets I have successfully employed the machine illustrated in the accompanying drawings. This machine includes a supporting 75 structure 2 carrying a base plate 3 and having standards 4 extending upwardly from the latter so as to provide guides for a reciprocable plunger 5. The standards also have bearings for a shaft 6 on which is mounted 80 a driving pulley 7 and an eccentric whereby the plunger 5 is actuated through a rod 8. The base structure 3 is preferably of an inverted U-shaped section, being elongated transversely of the machine and having 85 screwed or bolted to its flat top face two elongated blocks 9 and 10 which with an intermediate plate 11 (Figs. 4 and 7) constitute the die of the machine.

This plate 11 is clamped between the 90 blocks 9 and 10 by screws or bolts 12 passing horizontally through the ends thereof, and the adjacent faces of these blocks (Figs. 7 and 8) are undercut longitudinally below a line extending parallel with the top edges 95 some distance below the same; said edges being vertically recessed so as to coöperate with the plate 11 in defining two parallel series of narrow elongated punch receiving openings 13, although it is obvious that 100 the openings may be arranged in other groupings without departing from my invention. Said plate is supported with its top edge flush with the top surface of the two die members 9 and 10, for which purpose the end portions of these have their adjacent faces cut away as indicated at 15, Fig. 8 to provide shoulders upon which it may

rest. The plate 11 is also supported intermediate of its ends by shouldered projections 16 extending toward and under it at suitable intervals from the adjacent undercut faces of the blocks 9 and 10. If desired the end portions of the plate may have their lower portions laterally thickened as shown at 11^a Fig. 9 in order to provide extended surfaces for engagement with the supporting shoulders of said blocks.

The punches 17, which preferably consist of flat strips of spring steel concaved or sloped at their lower ends, are clamped in two parallel series between a pair of elongated blocks 18 and 19 by means of screws or bolts 20 passing transversely through the end of the latter. These blocks are mounted in a suitable recess in the under side of a head 21 carried by the lower end of the plunger 5 where they are held by vertically extending screws shown in dotted lines in Fig. 4 and passing through openings 22. The adjacent faces of these blocks 18 and 19 are vertically slotted to receive the punches 17 and a plate 25 is clamped between them to space the latter in such positions that they will properly enter the openings 13 in the lower die. The upper ends of the punches abut upon the flat bottom of the recess of the head 21 in which the blocks 18 and 19 are mounted and as they are arranged in adjacent pairs, they are held from dropping out of their recesses by pins 26 each of which passes transversely through said blocks, the spacing plate 25 and one pair of the punches 17. The punches themselves are made of suitable steel such as that commonly employed in clock springs and the lower or work engaging end of each of them may be concaved from edge to edge as shown in Fig. 5.

For guiding and laterally supporting the parts of the punches 17 which project below the blocks 18 and 19, I provide a guide block consisting of two flat plates 27 and 28 held together in the same plane by screws 29 passing horizontally through their end portions, and held apart by a thin vertically extending spacer 30. The edges of these plates adjacent said spacer are vertically recessed as indicated at 31 to permit the close passage through them of the punches 17, and the guide block is screwed or otherwise rigidly held to the top face of the die structure 9-10, having its under face recessed to form a sheet guiding slot or way immediately above the flat face of said structure. The vertical height of this slot is merely sufficient to permit of the free sliding through it of the rubber or other sheets to be punched, so that the guide plate 27-28 not only acts to direct each sheet but also serves as a stripper to prevent it moving upwardly with the punches as they are withdrawn after having been forced through it.

For intermittently feeding sheets through the machine I provide a pair of nip rolls 35-36 of which the latter is mounted in suitable bearings formed in the branches of a U-shaped supporting structure 37 adjustably held to the base plate 2 by a bolt 38 passing through an elongated slot 39 in said structure. This roll is preferably longitudinally corrugated or ribbed, while the upper roll, which is supported in bearings 40 immediately above it, is circularly ribbed or corrugated. The bearings 40 are slidably mounted on studs 41 fixed in the arms or branches of the supporting structure 37 and are acted on by springs 42 mounted on said studs in such a manner as to at all times yieldingly press the roll 36 toward the roll 35;—the parts being so arranged that a substantially horizontal plane including the guide slot between the blocks 27-28 and the die 9-10, includes also the line of tangency of said rolls.

The spindles on which the rolls are mounted in the present case have fixed to them two coating pinions 43 and 44 and one of said spindles also has fixed to it a ratchet wheel 45 kept from turning in one direction by a spring actuated pawl 46. For actuating this pawl I provide a pin 47 projecting eccentrically from one end of the shaft 6 and through a rod 48 I connect this pin with an arm 49 mounted to swing on the spindle 50 on which the roll 35 is fixed. The pivot 51 connecting the rod 48 and the arm 49 also serves to carry a pawl 52 acted on by a spring so as to normally engage the teeth of the ratchet wheel 45. It is noted that the feed rolls 35 and 36 are supported at the rear or back side of the die 9-10 and for guiding the blank sheet prior to its engagement by the punches, I provide a flat tubular guideway 53 supported across the front of the machine on a pair of brackets 54 fixed to the structure 3.

Under conditions of operation power is applied to the pulley 7 so that the plunger 5 with the head 21 and its punches 17 are vertically reciprocated, and the resulting reciprocation of the rod 48 causes the pawl 52 to intermittently turn the ratchet wheel 45 with the feed roll 35. If now a blank sheet of hard rubber of the proper thickness and width be fed through the guideway 53 and entered in the slot or recess 56 between the die blocks 9-10 and the guide plates 27-28, it will ultimately be engaged by the two sets of punches 17 and have formed in it two lines of narrow elongated slots 1. Each time the head 21 with the punches is raised the sheet is fed inwardly until it is engaged by the rollers 35-36 and thereafter the pairs of lines of slots 1 are formed in it at the desired distances apart, which distances are usually slightly more than the thickness of the punches. The punchings formed

pass down through the cavity 57 (Fig. 4) defined by the undercut portions of the die blocks 9 and 10 and from thence fall out through a suitable passage 58 in the die 5 supporting structure 3.

From the above description it will be noted that while the punches are so held as to be rigidly supported both laterally and at their ends, their mounting is such that by 10 removing the blocks 18 and 19 from their recess in the head 21, it is possible to quickly remove and replace any desired number of punches by forcing out the pins 26 whereby they are held in place. Moreover the sheet 15 operated on is so guided and held during the punching operation that it is effectually prevented from buckling, and I have found that owing to the peculiar arrangement of the ribs or corrugations upon the feed rolls 20 said sheet is firmly held by reason of the small temporary indentations caused in it by said rolls, so that its slippage is effectually prevented and its positive feed is assured. Further, by having the feed rolls 25 ribbed as noted, the punchings which adhere to the sheet owing to its electrified condition, are not pressed into it by the rolls but are moved into the depressions between the ribs so that they do not affect said sheet.

30 I claim:

1. The combination in a punching machine of an elongated series of punches; a die; and a pair of rolls for feeding sheet material 35 between the die and punches, said rolls respectively having ribs substantially at right angles to each other.

2. The combination in a punching machine of an elongated series of punches; a die; and a pair of rolls for feeding sheet 40 material between the die and punches, one of said rolls being longitudinally ribbed and the other being circumferentially ribbed.

3. The combination in a punching machine of a reciprocatory head; a pair of 45 blocks; a series of punches mounted between the blocks; pins extending through the punches into the blocks for holding said punches from longitudinal movement; means for clamping the blocks and punches 50 to the head; and a die having openings for the reception of the punches.

4. The combination in a punching machine of a head; two blocks mounted thereon; a punch between said blocks; a pin extending into the blocks and through the punch for holding it against longitudinal movement; means for clamping the blocks and the punch to the head; a die having an opening for said punch; and means for reciprocating the head.

5. The combination in a punching machine of a reciprocatory head; a punch 55 mounted in said head; a pin extending through said punch for holding it against longitudinal movement; means in addition

to said pin for clamping the punches to the head; and a die mounted to coact with the punch.

6. The combination in a punching machine of a reciprocatory head; a plurality of punches mounted in said head; a pin extending through said punches to hold them from longitudinal movement; means in addition to said pin for clamping the punches in the head; and a die mounted to coact 75 with the punches.

7. The combination in a punching machine of a reciprocatory head; a plurality of sets of punches mounted in said head to extend in parallel lines; a series of pins each 80 engaging the punches of one set for independently holding them from longitudinal movement; means other than the pins for clamping the punches in the head; and a die mounted to coact with said punches. 85

8. The combination in a punching machine of a reciprocatory head; two blocks; a spacing piece mounted between the blocks; two series of punches respectively mounted between the blocks and the spacing piece; 90 with a die having openings for said punches.

9. The combination in a punching machine of a reciprocatory head; two elongated blocks connected thereto; a spacing piece extending between said blocks; two series 95 of punches respectively mounted between said plate and the two blocks; pins extending through the blocks and the spacing piece and each engaging two of the punches; with a die mounted to coöperate with the 100 punches.

10. The combination in a punching machine of a reciprocatory head; two blocks connected thereto; a plate mounted between the blocks; flat blades constituting punches 105 clamped in two series between the blocks and said plate; removable pins extending through the blocks and the plate and each engaging two of the punches; with a die mounted to coöperate with the punches. 110

11. The combination in a punching machine of a reciprocatory head; at least two punches mounted therein; a die mounted to coöperate with said punches; with a stripper mounted between the head and the die, 115 said stripper consisting of two plates having their adjacent edges recessed for the reception of punches and an intermediate plate mounted between said recessed plates and coöoperating therewith to define the 120 punch receiving openings.

12. The combination in a punching machine of a reciprocatory head; two lines of punches mounted therein; and a die coöperating with said punches, having openings 125 for the punches, said die consisting of two blocks and an intermediate plate mounted between the same.

13. The combination in a punching machine of a reciprocatory head; at least two 130

punches mounted therein; with a die consisting of two blocks having their adjacent edges undercut and recessed for the reception of the punches and an intermediate plate extending longitudinally between said blocks to define the punch receiving openings.

14. The combination in a punching machine of a reciprocatory head; a plurality of series of punches mounted therein; with

a die consisting of two blocks having their adjacent edges recessed for the reception of the punches and formed with shouldered portions; with a plate extending between said blocks and supported on said shouldered portions in position to coöperate with the blocks to define punch receiving openings. 15

In witness whereof I affix my signature.

VICTOR R. BOTTONE.
